PRICE-CONTROLLED FUEL PUMP

Toby B. Harper, Dolph, Ark.

Application June 18, 1954, Serial No. 437,815

5 Claims. (Cl. 222—16)

This invention relates to a price-controlled fuel pump and has for its primary object the provision of a simple, compact and inexpensive control system for a fuel pump which can be preset to automatically deliver a given amount of fuel in terms of the total price of the fuel to be delivered.

In order to avoid the nuisance of waiting for change after purchasing gasoline, for example, the customer often asks for an amount of gas corresponding to what he wishes to pay or to the change he may pull out of his pocket. Most often, the customer will ask for an even amount, such as "\$2.00 worth of gas," or \$3.00 or \$4.00 worth, as the case may be. A major object of the invention is to provide a device which can be preset by the pump operator to the desired price, and when the amount of fuel corresponding to that price has been delivered, the pump will automatically shut off.

Another object is to produce such a device which can be readily set by means of electric pushbuttons to the desired amount.

Another object is to provide such a device as an attachment to a standard pump with a minimum of alteration or connection to the existing pump.

The specific nature of the invention as well as other objects and advantages thereof will clearly appear from a description of a preferred embodiment as shown in the accompanying drawings, in which:

Fig. 1 is a schematic and circuit drawing of the meter-controlled switching system of my invention;

Fig. 2 is a side elevation of a counter-actuating solenoid for operating the number of dials and associated mechanism of my invention; and

Fig. 3 is a front elevation of a typical gasoline pump showing the manner in which my invention is attached thereto.

Referring to Fig. 3, a typical gas pump 2 is provided with the usual meter face 5 for registering the unit price of gasoline, the number of gallons delivered and the total price of the gas delivered. Such pumps, as is well known, are electrically driven and are usually controlled by a hand-operated lever near the nozzle. Some pumps in common use are equipped with automatic nozzles which shut off the pump flow when the tank is filled, by means of an electric solenoid operating on the shut-off mechanism of the pump. It will be apparent that electrical control of the cut-off operation may be accomplished either by a relay which cuts off the entire electrical supply to the pump or by a solenoid of known type mounted on the end of the hose adjacent to the nozzle to produce the same shut-off operation as is normally done by the hand of the pump operator. For the purpose of illustration only, I show the latter type in Fig. 3 at 6, being mounted on the end of the fuel delivery hose 8, and provided with insulated circuit wires 10 which may be coiled around the hose and in contact therewith, or otherwise secured thereto. When the circuit is closed to the solenoid or to the relay, the supply of gas will be abruptly stopped.

2

As shown in Fig. 3, I provide a box or casing 12 which may be attached to the pump on the same side, 4, as face 5, and which contains most of the components of my invention. The front of this casing 12 shows three number wheels 14 which may be made more or less like the price indicators in face 5 of the pump, to indicate dollars and cents up to \$9.99, which is all that is required for most purposes, although if the price of gasoline continues to rise, it may be desirable to add a fourth number wheel for tens of dollars.

One direct attachment to the existing price indicator is necessary. It is required to attach a toothed wheel 16 (Fig. 1) to the unit cents wheel (that is, 0-9¢, the last price wheel on the right) which will rotate together with the unit cents wheel. The toothed wheel is provided with teeth which open and close a switch 26 ten times for each revolution of the unit cents wheel, so that for every penny registered on the price indicator 5, a circuit controlled by the toothed wheel can be opened and closed once. Thus electrical pulses are provided for the operation of my device.

The circuit controlled by the toothed wheel 16 is shown in Fig. 1. A separate housing 18 is shown attached to pump 4 for toothed wheel 16. Shaft 19 of the toothed wheel extends into the pump 4 and is coupled into unit cents wheel 7 in any suitable manner, depending on the physical arrangement of the pump elements, either directly or through suitable gearing so that toothed wheel 16 is driven in the desired relationship with the unit cents wheel of the pump. A manually-operated switch 20 is also provided in housing 18 having two sets of contacts 20a and 20b, for disconnecting the entire system so as to enable the pump meter to be reset to zero after each sale without effecting the operation of my device, which is automatically reset to zero at the end of each filling operation. Also, where the amount of gas to be bought is not announced in advance, there is no need to use my device, and switch 20 can then be left open.

Terminals 22 and 24 of my device are connected to any suitable source of current, e. g., 110 volts A.-C., which supplies the power for operating the device. When the circuit is closed, current flows from terminal 22 through switch contacts 20a and switch 26 each time contact is made due to the action of the teeth of wheel 16, which is shown as having ten teeth, therefore the circuit will be closed at 26 each time another penny registers on the main meter 5. Each resulting current pulse passes down wire 28, through closed contact 30b along wire 32 to solenoid 34.

Solenoid 34, when energized, pulls in a magnetic plunger 36 as shown in Fig. 2, which swings lever 38, pivoted at 40, and retracts pawl 42 one tooth back on toothed ratchet wheel 44. Adjustable stop means are provided on pin 46 for limiting the travel of the pawl at each stroke as required for proper operation, and tension means 48 can be readily adjusted to any desired tension by setting spring 50 to the desired point on lever arm 52. The pawl operation is thus regularly and completely adjustable.

Ratchet wheel 44 rotates freely on shaft 54, which may also serve as the shaft for two identical ratchet wheels 56 and 58 as shown in Fig. 1.

Attached to the ratchet wheel 44 for rotation therewith as a rotary unit on shaft 54 are a number wheel 60 bearing the numbers from 0-9, an eccentric cam 62 for actuating a switch 64 once for each tenth pulse received by solenoid 34, and a brake pulley wheel 66 for providing controlled friction between the rotary unit and its shaft.

Suitable stops 68 and 70 may be keyed to shaft 54 to ensure retention of the rotary unit in the proper position with respect to solenoid 34. A V-belt 72 is provided

which is tensioned and anchored by spring 74 to provide sufficient friction for the rotary unit on shaft 54, to insure that retraction of pawl 42 does not change the position of the rotary unit, but forward motion of pawl 42 under the action of spring 48, on cessation of the current pulse, is sufficient to overcome the light friction provided by the brake and advance the ratchet one tooth. If desired, a stationary spring pawl can be provided to insure that reverse motion of the ratchet wheel cannot take place, but with the system shown this is not necessary.

To continue with the circuit for energizing solenoid 34, the remaining terminal of the solenoid is connected to line 76, which leads back to the other terminal 24 of the external power source.

The numbers on the number wheel 60 are placed thereon in backward relation to the numbers on the corresponding unit cents wheel 5 of the pump, so that each time a penny more is registered on the pump dial, a penny less is registered on dial 60. The reason for this will be explained later.

Insulated cam 62 is so arranged that once each complete revolution of dial 60, when the dial registration is passing through zero, the cam 62 actuates switch 64 to close both of the two circuits controlled by this switch momentarily. Upper switch 64a therefore closes a circuit momentarily from switch 26 controlled by toothed wheel 16, line 28, line 80, switch 64a, line 82, line 84, normally closed switch 86b, line 88, to the second solenoid 90, and from the other terminal of this solenoid back through line 76 to input terminal 24 as previously described. Thus it will be seen that whenever the unit wheel has indicated its tenth penny, it is reset to zero, while the next number wheel to the left, which indicates tens (or dimes) is notched up one number. Solenoid 90 is identical with solenoid 34 and on registering its tenth dime, its cam 92 actuates its switch 94a in the same fashion to close a circuit extending from previously closed switch 64a, wire 82, wire 96, switch 94a, wire 98, normally closed switch 100a, wire 102, normally closed switch 104a, wire 106 to the dollar solenoid 108, and back from this solenoid to wire 76 as before. Thus every tenth operation of solenoid 90 will reset its unit wheel to zero and register another unit on the dollars wheel. The timing of the insulated cams 62 and 92 is, of course, so phased with respect to the respective teeth of toothed wheel 16 that switches 26, 64a, and 94a are all closed simultaneously so that a pulse from switch 26 can be transmitted through the other two switches in series.

The solenoid mechanism associated with solenoid 108 is identical with those of solenoids 34 and 90, but it will be noted that its associated switch 100a is different in that it is normally closed instead of being normally open like the previously described switches. Thus, when the dollar indicator is reset to zero, its insulated cam 110 at this moment opens switch 100a, and the cam face is arranged to have a sufficiently long dwell so that while the dollar wheel is indicating zero dollars, switch 100a remains open. Since the operation of my device is completed when all three dials indicate zero, this insures that at the conclusion of operation, the solenoid circuit is open, and the dollar indication can go no further.

Whenever the dollar indicator first reads zero, the other two indicators are necessarily also zero, since they are so set, and switches 64b, 94b, and 100b are all closed. A circuit is thus established through all three of these switches in series, from terminal 22, through line 78, switch 64b, line 112, switch 94b, line 114, switch 100b, line 116, through shut-off solenoid 6, line 120, manual switch 20b, and back through line 122 to input terminal 24. This causes the solenoid to be actuated and the gas pump to be shut off. Initially, of course, the dials of my device had been set to the desired amount, and while gas was being delivered, the number wheels

were being stepped backward from the desired amount toward zero. Thus when zero is reached, the desired amount is now registered on the main price meter of the fuel pump and due to the action of switches 64b, 94b, and 100b as described above, the pump is shut off, which is the desired result.

It will now be shown how the desired amount is initially registered on the three dials of my device. For this purpose I provide three pushbuttons 124, 126, and 128, respectively associated with solenoids 34, 90 and 108. When pushbutton 124 is depressed, it opens switch 30b and closes switch 30a. This closes a circuit from input terminal 22, through line 130, through switch 30a, line 32, solenoid 34, and back to line 76 as before. This retracts the solenoid plunger and upon release of button 124 the number wheel 60 is stepped back one number. When pushbutton 124 is depressed a second time, number wheel 60 is stepped back another unit. It can readily be seen that pushbuttons 124 and 126 operate exactly the same way, that is, whenever each one of them is depressed once, the associated number wheel is stepped one unit. Thus, by pressing each pushbutton a number of times corresponding to the price desired, the total price can be set up in advance. In practice, since an integral number of dollars worth of gasoline is usually required, it is almost always necessary only to push plunger 128 a few times, since this is almost always in the range of the amount desired. However, if an odd number of pennies' worth of gasoline is also required, this can readily be registered by manipulating the pushbutton the necessary number of times.

It will thus be seen that I have provided a simple device which can be inexpensively made out of a few standard units, such as standard stack switches, and other common parts such as pawl and ratchet solenoid control mechanisms, etc. Alternatively, the unit wheel for each solenoid may be readily assembled from inexpensively made stampings or castings. The device is also simple and practically foolproof in operation, and can readily be attached to any standard pump of the various types now in common use.

Instead of the ratchet plunger operating to step the ratchet wheel on the return stroke by spring action, it could obviously be stepped on the initial stroke and merely reset by the spring. Likewise, the normally open circuits could be operated as normally closed circuits, and vice versa.

It will be apparent that the embodiments shown are only exemplary and that various modifications can be made in construction and arrangement within the scope of my invention as defined in the appended claims.

I claim:

1. For use with a fuel pump having a price meter for indicating continuously the total price of the fuel pumped, means for shutting off the pump when the price reaches a predetermined amount, comprising: a second price meter manually adjustable to said predetermined amount, and operable backward toward zero setting as gas is pumped, and switch means operated when said second meter reaches zero setting to stop the flow of gas from said pump, said second price meter comprising separate number wheels rotatable to display the respective digits of the price, each fixed to a ratchet wheel having ratchet teeth corresponding to the number of digits on each number wheel, a solenoid for each ratchet wheel, a pawl for each ratchet wheel actuated by each said solenoid to step said ratchet wheel one step each time the solenoid is energized and deenergized and thus step the price count by one digit, means actuated by the fuel meter of the pump for completing one cycle of energization and deenergization of the cents wheel of said second meter for each cent's worth of fuel pumped and a cam rotatable with each number wheel, a switch for each wheel except the highest order, operable by its cam 65 when the number wheel passes through a given number

setting to control the energization of the solenoid of the next higher order wheel up to the last one.

2. The invention according to claim 1, and a switch for the highest order wheel arranged to deenergize all of the solenoids at the zero setting of said highest order wheel.

3. The invention according to claim 2, and a manually operable switch for each solenoid for individually stepping each solenoid to a desired setting.

4. In a fluid dispensing apparatus, a pump for producing flow of liquid, a cost meter connected to be driven by said flow to register the cost of the fluid dispensed, a rotary element connected to said cost meter, a pulsing circuit controlled by said rotary element to produce a fixed number of pulses for each revolution of said rotary element, a second cost meter comprising a plurality of number wheels rotatable to display the respective digits of the desired cost and arranged to count backward from said desired cost as said first cost meter counts forward toward said desired cost, means for setting said second cost meter to a desired cost reading, switch means operable by each number wheel as it

reaches zero setting, and a circuit controlled by the concurrent operation of all said separate switch means to cut off the flow of fluid.

5. The invention according to claim 4, said means for setting the second cost meter comprising an individual manually operable switch means for each number wheel, a separate solenoid operated ratchet for each number wheel, and circuit means for connecting a source of power to each solenoid through its switch means each time said switch means is manually operated to step each number wheel one unit each time its associated switch means is manually operated, to thereby set each number wheel to a desired digit.
